UNITED STATES PATENT OFFICE.

WILLIAM MINGLE AND HENRY M. JACKSON, OF MONTREAL, QUEBEC, CANADA, AS
SIGNORS TO SIMMONS LIMITED, OF MONTREAL, QUEBEC, CANADA.

BED.

Application filed June 23, 1924. Serial No. 721,916.

This invention relates to improvements in beds and more particularly to beds of a type intended for hospital or invalid use and having the bottom articulated to provide back 5 and leg supports which may be adjusted to various degrees of inclination.

The primary object of the invention is to provide simple, durable and efficient means for adjusting the inclination of the bottom 10 sections, said means being so constructed as to relieve the bed proper of certain stresses pertaining peculiarly to the raising and lowering of the bottom sections.

A further object is to provide in a device 15 of this character a permanently connected operating handle which may be folded under the bed and out of the way when not in use.

Various other objects and advantages may 20 be ascertained from the following description and the accompanying drawings.

The type of bed to which this invention relates embodies a rigid main frame, upon 25 which is mounted an articulated bed bottom, the several sections of which are provided with means for holding them at various inclinations. The supporting means of the bottom sections most commonly used engage in notched holding members and as a 30 result the number of positions to which the bottom sections may be adjusted is limited by the number of notches in the members. Adjusting devices have been proposed embodying a right- and left-hand screw journaled 35 on the main frame and carrying nuts linked to the bottom section to be adjusted. Such an arrangement has the great disadvantage that when the bottom sections are lowered the elevating links are nearly in parallelism 40 with the screw so that, particularly at the commencement of the elevating operation, there is a very great outward thrust on the bottom frame which can be counteracted only by the use of numerous cross-ties or unneces- 45 sarily heavy frame members.

According to the present invention, a screw operating gear is provided in which the stresses are equalized in the gear itself, so that there is no thrust upon the bed frame, 50 thus enabling the use of lighter frames and the elimination of cross-ties to resist thrust, thereby materially reducing the cost of the structure besides presenting additional advantages which will be hereinafter dealt 55 with. The operating gear comprises a right-

and left-hand screw journaled on the main frame of the bed and carrying adjacent each end thereof a loose collar. Right- and left-hand nuts are provided on the screw and connected by links to a movable section of the 60 bed bottom. These links are connected midway between their ends to the collars by further links and the collars at opposite ends of the screw are connected to one another by links. 65

In the accompanying drawings which illustrate one embodiment of the invention, but to the specific details of which the invention is not confined:—

Fig. 1 is a side elevation of a bed having 70 an articulated bottom.

Fig. 2 is a plan view of same.

Fig. 3 is a cross sectional view on an enlarged scale at the plane of an operating gear. 75

Fig. 4 is a fragmentary bottom plan view showing the mounting of the operating crank.

Referring more particularly to the drawings, 11 designates the rigid main frame of 80 a bed which may be constructed in any usual or suitable manner. Mounted upon this rigid frame is an articulated bed bottom comprising an anchor section 12 fixedly related to the frame 11; a head section 13; a leg section 14 and a foot section 15. The sections 13 and 14 are hingedly related to the section 12, and the section 15 is hingedly related to the section 14. The construction of these sections may be as desired and their number 85 may be increased or diminished according to the particular service for which the bed is adapted. Only the frames of these sections are illustrated, but it will be understood that any usual or suitable type of bottom fabric will be mounted in the articulated bottom frame. In order to hold the side members of the frame against being drawn together by the weight of a person resting on the bottom fabric, drop braces 16 are provided as necessary on the bottom sections. In the particular type of bed illustrated, elevating gear is 95 provided for the head and leg sections only, the foot section being supported by special means comprising at each side of the bed a notched bar 17 pivotally related at one end to the bottom frame, preferably at the jointure of the leg and foot sections, the opposite ends of these bars rest upon the main frame 11 and are tied together across the 100

105

110

bed by a rod 18. Guide ribs 19 are secured to the main frame, for example, within the bars 17 to hold them against lateral movement, such as would disengage them from the main frame. Links 20 are pivotally connected to the opposite sides of the foot section and are connected at their free ends to one another by a rod 21 adapted to rest in the notches of the member 17 to support the foot section at various inclinations relatively to the horizontal and also relatively to the leg section 14. The bars 17 and rod 18 constitute a frame and the links 20 and bar 21 constitute a second frame, which two frames both pivotally relate to the bed bottom to operate to form adjusting means therefor. The number of elevating gears employed may be increased or diminished as desired or according to the number of adjustable sections in the bed bottom. The various elevating gears are similar and therefore one only will be described.

The operating gear embodies a right- and left-hand screw 22 extending transversely of the bed under the main frame and beneath the section to be adjusted. This screw is journaled adjacent its ends in suitable brackets 23 secured to the main frame 11. End collars 24 are fixed to the shaft outside the bearings 23 to hold the shaft against movement in its axial direction. These collars are diametrically slotted, as at 25, to receive one end of an operating crank 26, which may be pivotally connected to the collar by a pin 27. The crank is offset, as at 28, a sufficient distance to enable it to swing clear of the main frame 11, the offset serving also when the crank is swung round its pivot 27 from the operative position shown in full lines Figure 4 to the inoperative position shown in broken lines to enable the crank to pass through the vertical plane of the outside web of the angle iron usually used in the construction of bed frames. When thus swung inwardly the crank is entirely out of the way but may be swung out for use in a moment of time. When in operating position a lug 29 on the crank, bearing against the bottom of the slot 25, holds the crank against movement inwardly such as would permit it to strike the bed frame. The crank being connected to the screw is safeguarded from loss and is always available for immediate use. The employment of slotted collars at each end of the screw makes it possible to attach the crank to either end of the shaft as may be dictated by the location of the bed.

A pair of nuts 30 are mounted on the screw on opposite sides of the centre so that upon rotation of the screw these nuts, if held against rotation with the screw, will move in opposite directions. A block 31 is pivotally connected to each side of a bottom frame section, either directly or by means of a bracket 32. Links 33 are pivotally connected

at their ends to the nuts 30 and the adjacent blocks 31, and hold the nuts against rotation with the screw, the links being preferably formed of flat metal bars and arranged in pairs, so that the nuts, blocks and screws are 70 between the links of each pair. Obviously, a one-piece cast or forged link, bifurcated at its ends, may be substituted. Preferably the point of attachment of the nuts and links is located below the screw. Collars 34 are 75 loosely mounted on the screw adjacent the ends thereof and preferably in contact with the inner faces of the bearing brackets 23. These collars have no operative engagement with the screw threads and therefore will not 80 travel on the screw when the same is rotated but the screw will rotate within the collars. Links 35 are pivotally connected at their lower ends to the collars and hold the collars against rotation with the screw. These links 85 are pivoted at their upper ends to the links 33 at a point midway between the pivoted centres of the links 33. Between pivoted points the links 35 are exactly half the length of the links 33. The pivotal points of the links 33 and 35 on the nuts 30 and collars 34 respectively are disposed preferably all in one straight line parallel with the axis of the screw. The collars 34 at opposite sides of the bed are connected to one another by 90 links or tension rods 36, which may conveniently be connected to the collars by the same pivots which connect the links 35.

The position of the parts which the bed bottom section is lowered to rest on the main frame is illustrated in broken lines, Figure 3, and it will be observed that the position of the links 33 approaches parallelism with the screw. In practice the angle between the links and screw in the lowered position of the 105 bottom section is made as great as possible by disposing the screw some distance below the main frame. When the screw is rotated in the proper direction the nuts 30 move apart and tend to carry the links 33 outwardly with 110 them. The links 35, by reason of their angular relation with the links 33, resist this tendency and cause the links 33 to swing upwardly so that the bed bottom section to which they are connected is raised. The outward movement of the nuts produces a tendency to outward thrust through the links 33 against the bottom frame, but this outward thrust is transmitted through the links 35 to the collars, so that the tendency is to thrust 115 outwardly against the bearings 23 and through them against the main frame 11. The outward thrust is, however, transmitted from collar to collar through the links 36 so that the outward thrust on one side of the bed neutralizes the outward and opposite thrust on the other side of the bed, and thus 120 relieves both the bed bottom frame and the main frame of all outward thrust due to the movement of the nuts. The collars 24 which, 125

while nominally for the purpose of holding the screw against movement in its axial direction, function but slightly in this manner owing to the counter-balancing of forces acting on the screw. These collars in reality function only in the event of load being greater at one side of the frame section than at the other. The lengths of the links 33 and 35 and the disposition of their pivotal points on the nuts and collars compel the upper ends of the links 33 to move in a vertical path and thereby not only relieve the bottom frame of outward thrust but enable the links 33 to support the sides of the frame section against being drawn together by the weight of a person on the bed bottom. The blocks 31, being pivotally connected to the bottom frame section and the whole gear being free to swing around the axis of the screw, it will be evident that the links will incline freely from the vertical toward the ends of the bed as the bottom sections are moved. The load on the bed bottom operates through the linkage as an outward thrust on the collars 34 and as these opposite thrusts neutralize through the links 36 the only load transmitted to the main frame is vertically downward.

Having thus described our invention, what we claim is:

1. In a bed, a main frame, an articulated bed bottom supported thereon, and adjusting gear for the bed bottom comprising a right- and left-hand screw disposed transversely of the bed, nuts thereon, linkage between said nuts and the sides of the bed bottom frame, thrust collars within which said screw turns, and further links half the length of said first links connected between the medial points of said first mentioned links and the thrust collars whereby the ends of said first links con-

nected to the bottom frame are compelled to move vertically and the outward thrust of the nuts is transmitted to the collars, and links connecting the thrust collars on opposite sides of the bed.

2. A bed comprising a main frame, an articulated bed bottom supported thereon, bearing brackets depending from the main frame, a right- and left-hand screw journaled in said brackets, thrust collars freely revoluble on said screw without travel thereon between the brackets, nuts on the screw, links connecting said nuts and the sides of a section of the bed bottom, further links extending between the first links and the collars, and links connecting the collars at opposite sides of the bed, and thrust collars fixed to the end of the screw outside the brackets holding the screw against movement in its axial direction.

3. In a bed, a main frame, an articulated bed bottom supported thereon, and means for adjusting the inclination of the bed bottom comprising a right- and left-hand screw disposed transversely of the main frame and journaled thereon, nuts on said screw and links pivotally connected between said nuts and the bed bottom, the said links at each end of the screw being disposed on each side of the nuts and the point of pivotal attachment being disposed beneath the screw, thrust collars at the ends of the screw, further links connected between the first links and the collars at points beneath the screw, and links connected directly between the collars at points beneath the screw.

In witness whereof, we have hereunto set our hands.

WILLIAM MINGLE.
HENRY M. JACKSON.
